UNITED STATES PATENT OFFICE.

HARRY LEE ADAMS, OF ELVINS, MISSOURI.

GASOLINE ENGINE.

Application filed May 21, 1927. Serial No. 193,338.

This invention aims to provide a novel cylinder and piston construction for an internal combustion engine, together with a novel form of interengaging elements whereby rotation will be imparted to the piston, as the piston reciprocates, the aforesaid rotation of the piston serving to open and close the intake port and the exhaust port.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention hereinafter disclosed, may be made within the scope of what is claimed, without departing from the spirit of the invention.

In the drawings:

Figure 1 shows in longitudinal section, a device constructed in accordance with the invention, the cutting plane passing through the exhaust port;

Figure 2 is a longitudinal section taken through the intake port;

Figure 3 is an elevation of the piston;

Figure 4 is an elevation of the port plate that is mounted in the piston;

Figure 5 shows the cylinder surface developed;

Figure 6 is a section on the line 6-6 of Figure 5;

Figure 7 is a view resembling Figure 5, but showing a modification.

The crank case 1 of the engine carries a water jacketed cylinder 2 upon which is detachably secured a water jacketed head 3 having a hollow extension 4 which projects into the cylinder 2, the extension being spaced from the inner surface of the cylinder 2, as shown at 5 in Figure 1. The base of the extension 4 carries a spark plug 6 or other firing means.

The cylinder 2 has an exhaust port 7 communicating with an inclined groove 8 in the inner surface of the cylinder. The cylinder

2 has an intake port 9 communicating with an inclined groove 10 in the inner wall of the cylinder. The ports 7 and 9 are spaced apart circumferentially of the cylinder, and longitudinally of the cylinder, as Figure 5 will show, the port 7 being located at one end of the groove 8, and the port 9 being located at the opposite end of the groove 10. The grooves 8 and 10 are disposed at an angle to each other, and they incline circumferentially of the cylinder, as seen in Figure 5.

The grooves 8 and 10 are located between shallow V-shaped grooves 16 in the cylinder wall. The grooves 16 communicating at their lower ends with passages 17 extending downwardly in the cylinder wall to any suitable means 170 whereby the oil collected in the grooves 16 is returned to the crank case. The object of the grooves 16 is to keep surplus oil from working into the grooves 8 and 10, and, consequently, into the intake port 9 and the exhaust port 7.

The inner surface of the cylinder 2 is supplied with a circumferential zig-zag guide groove 11 defining first angles 12, the guide groove having enlargements 14 forming second angles 15 which are out of alignment with the angles 12, longitudinally of the cylinder, there being an enlargement, and the angles specified, at each end of each branch of the zig-zag guide groove.

The piston 18 is of tubular form and slides on the extension 4 of the head 3, within the cylinder 2. The piston 18 is provided with an intermediate partition 19, carrying a boss 20 on which is removably held a ball 21 at the end of a pitman 22 which is connected to the crank 23 of the engine shaft, the construction being such that when the piston 18 reciprocates, it can rotate on the pitman 22. A packing ring 24 on the part 4 of the cylinder head 3 makes a tight joint with the piston 18, as the piston reciprocates. The piston 18 is provided with lateral projections 25 which move in the zig-zag guide groove 11 of the cylinder 2, to impart rotation to the piston, as it reciprocates. There is a polygonal opening 26 in the piston 18 which communicates with a smaller circular opening 27 in the piston. A port plate 28 is

provided and is shaped to fit closely in the opening 26 of the piston, the port plate having an extension 29 of circular form, to fit in the part 27 of the opening in the piston wall. The plate 28 has a port 30 which extends through the part 29 of the plate, the port 30 communicating with the chamber 31 which exists in the piston 18, between the partition 19 and the base of the member 4 of the cylinder head 3. The port 30 has a straight lower edge 300.

When the piston 18 reciprocates, the projection 25 on the piston 18 moves in the zig-zag guide groove 11 of the cylinder 2, and cause the piston 18 to rotate, thereby bringing the port 30 of the piston 18 into communication with the intake groove 9 and the exhaust groove 8, in properly timed relation, so that the fuel may be admitted to the chamber 30 and the exhaust be ejected therefrom. The compression in the chamber 31 holds the port plate 30 of the piston 18 in intimate contact with the inner wall of the cylinder 2, owing to the fact that the body portion of the plate forms, in substance, a flange that projects beyond the periphery of the part 29, as shown in Figure 4. Because the angles 12 and 15 of the guide groove 11 are out of alinement, longitudinally of the cylinder, the projections 25 will not be received in the wrong part of the guide groove 11 and bring about a reverse rotation of the piston 18, when the right-line sliding movement of the piston is reversed. In the event that some person should demand a positive means for preventing accidental reverse rotation of the piston 18, spring pawls 32 may be located in the parts of the guide groove 11^a, as shown in Figure 7, each spring pawl being secured at one end, as at 33, to the cylinder. In this form of the invention, the ends of the projections 25 of the piston can ride over the free ends of the spring pawls 32 when the projections move in the direction of the arrow A in Figure 7: but the free ends of the spring pawls 32 will engage the projections 25 and stop the movement of the projections 25 in the direction of the arrow B in Figure 7, a reverse rotation of the piston thus being positively prevented.

Attention is directed to the fact that the lower edge of the piston port 30 is straight, as shown at 300, the edge 300 being flush with the upper surface of the partition 19 in the piston 18. It is to be recalled that as the piston 18 reciprocates, it rotates, as well, and because the lower edge 300 of the port 30 is flush with the upper surface of the partition 19 the piston will tend to free itself of surplus oil, by centrifugal action: that is, oil which might otherwise accumulate in the piston, will be whirled off the upper surface of the partition 19, through the port 30, into the exhaust port 7.

65 The engine described and claimed is of

the four-cycle type. On the exhaust stroke, the piston 18 moves upwardly and the port 30 in the piston comes into communication with the exhaust port 7. The piston makes a quarter turn, moving downwardly on the intake stroke, the port 30 coming into communication with the intake port 9. The piston moves upwardly on a compression stroke, making a quarter turn, the port 30 in the piston being in communication with neither of the ports 7 and 9: and, to complete the cycle, the piston 18 moves downwardly on the power stroke and makes a quarter turn, the port 30 in the piston being in communication with neither of the ports 7 and 9. 75 80

The general construction of this rotary piston engine is such that it does away with many moving parts; cams, countershafts, and valve shafts, being dispensed with, and there being no valves to set or grind, and no valve springs to break or wear out. 85

What is claimed is:—

1. In an internal combustion engine, a cylinder, a piston mounted to reciprocate and to rotate in the cylinder, the piston having a partition intermediate its ends, and there being a port in the side wall of the piston, the cylinder having intake and exhaust ports, and interengaging elements on the piston and on the cylinder, said elements cooperating to rotate the piston and to bring the port of the piston into communication with the intake and exhaust ports at different times, one edge of the port in the piston being flush with the transverse surface of the partition, whereby the partition will clear itself of oil, by centrifugal action, through the port of the piston and the exhaust port of the cylinder. 95 100

2. In an internal combustion engine, cooperating members including a cylinder and a piston mounted to reciprocate in the cylinder, the cylinder having intake and exhaust ports, and the piston being provided with a port, one of said cooperating members having a circumferential zig-zag guide groove comprising branches, and the other of said cooperating members having a projection slideable in the groove, the projection and the groove coacting to rotate the piston and to bring the port of the piston into communication with the intake and exhaust ports at different times, as the piston is reciprocated, and back-stop pawls in the branches of the groove, and constituting means for directing the projection from one branch of the groove into the other branch thereof. 110 115

3. In an internal combustion engine, a cylinder, a sleeve piston mounted to reciprocate in the cylinder and provided with a port, interengaging elements on the piston and on the cylinder, said elements cooperating to rotate the piston when the piston reciprocates, the cylinder having an exhaust port and an intake port and having grooves in which the 125 130

exhaust and intake ports are respectively located, the grooves being inclined circumferentially of the cylinder and located at an angle to each other, the port in the piston moving longitudinally of the grooves, in communication therewith, as the piston reciprocates and rotates, the cylinder having angular oil collecting grooves located on opposite sides

of the first specified grooves, longitudinally of the cylinder, the cylinder having outlets communicating with the oil collecting grooves. ¹⁰

In testimony that I claim the foregoing as my own, I have hereto affixed by signature.

HARRY LEE ADAMS.
